(57) **CLAIM**

The ornamental design for a slide clamp assembly, as shown and described.

DESCRIPTION

FIG. 1 is a front, top, and right-side perspective view of a slide clamp assembly, showing our new design;

FIG. 2 is a right-side elevational view thereof;

FIG. 3 is a left-side elevational view thereof;

FIG. 4 is a back elevational view thereof;

FIG. 5 is a front elevational view thereof;

FIG. 6 is a top plan view thereof; and,

FIG. 7 is a bottom plan view thereof.

The ornamental design which is claimed is shown in solid lines in the drawings. The broken lines depict portions of the article that form no part of the claimed design.

1 Claim, 7 Drawing Sheets
